MASONRY SIMULATING MATERIAL

Gilbert J. Snyder, South Bend, Ind., assignor to
 Mastic Asphalt Corporation, South Bend, Ind.,
 a corporation of Indiana

Application November 12, 1940, Serial No. 365,259

6 Claims. (Cl. 20—5)

This invention relates to masonry simulating material, and particularly to building covering material, such as siding material, formed on a panel foundation or base which is coated with water-proofing material and surfaced with granular material arranged or designed to simulate a plurality of masonry elements, such as brick faces, and mortar joints therebetween.

Considerable difficulty has been experienced heretofore in the manufacture of material of this character in obtaining a good simulation of masonry material, such as brick work. Thus, up to this time, it has generally been found, particularly with respect to material which is laid in co-planar, as distinguished from over-lapping relation, that most attempts to employ two colors of granular material upon the panel to simulate masonry faces and mortar joints, respectively, have been subject to exposure of the panel character of the built-up wall surface. This has been due to the fact that material such as asphalt, used to water-proof the panels and to cause the granular facing material to adhere thereto is of a dark color which is exposed at the edges of the panels. Hence, if the panels do not fit tightly and exactly one against the other at their abutting edges, the color of the water-proofing material is exposed at the cavities or joints, between the panels. On the other hand, it is practically impossible to achieve a uniform tight joint between panels by reason of the fact that the composition or insulation board which is generally used as a base for material of this character cannot be made of accurate size, and the manufacturers' tolerances for dimensions are usually plus or minus $\frac{1}{32}$ of an inch. These unavoidable tolerances result in the occurrence, in a surface of assembled panels, of a plurality of cavities at the joints or between the edges of adjacent panels. Various attempts to overcome this deficiency have been made but to the best of my knowledge the only method which has heretofore been successful in material using panels laid up in co-planar relation is that illustrated and described in the patent to L. H. Mattes, No. 2,205,798, dated June 25, 1940.

I have found, however, that there is another method by means of which the existence of cavities at panel joints may be concealed efficiently.

The primary object of my invention is to provide a novel construction of masonry simulating material by means of which the joints between adjacent co-planar elements or panels of said material may be concealed effectively.

A further object is to provide an article of this

character having masonry simulating faces of one color and mortar joint simulations of a second color including mortar joints extending to the edge of the panel at two adjacent sides thereof, with a narrow band of material of the same color as the mortar joint at and projecting from the other two sides of the panel to abut the adjacent panel and thereby conceal any cavity between panels when the panels are laid in co-planar substantially abutting relation.

A further object is to provide an article of this character having a thermo-plastic coating on one face and granules of two different colors covering said coating in a patterned arrangement simulating masonry faces and intermediate mortar joints, with a narrow band of granules of mortar joint color applied to certain edges of said coating in a plane at an angle to the coating.

A further object is to provide an article of this character having spaced masonry simulating areas thereof coated with granules of one color and the intermediate areas thereof coated with granules of a second color, wherein granules of the second color are applied at the edges of the panel complementary to the edges to which mortar joint simulations extend, and wherein one or more margins of the inner mortar joint simulating faces are provided with a narrow groove to complement the appearance of the joints between the edges of adjacent substantially abutting panels.

Other objects will be apparent from the description, drawing, and appended claims.

In the drawing:

Fig. 1 is a view in face elevation of a member embodying my invention.

Fig. 2 is an enlarged fragmentary sectional view taken on line 2—2 of Fig. 3.

Fig. 3 is an enlarged fragmentary sectional view taken on line 2—2 of Fig. 1 and illustrating a slightly modified embodiment of the invention.

Fig. 4 is an enlarged fragmentary sectional view illustrating a joint between adjacent panels leaving a cavity therebetween and also illustrating the manner in which the cavity is concealed.

Referring to the drawing which illustrates the preferred embodiment of the invention, the numeral 10 designates a panel of composition or insulation board such as "Celotex" or "Insulite." The panel 10 is made of any desired size and is provided at two adjacent edges with inset ship-lap flanges 11, and is undercut at two opposite edges to provide reduced thickness flange portions 12 complementary to the ship-lap flanges 11. The innermost faces of the flanges 11—12 lie

in the same plane and the transverse dimensions of the said flanges are the same, so that panels may be laid in abutting relation to provide a weatherproof ship-lap joint therebetween without substantially detracting from the continuity or appearance of the assembled panels, as is well understood in the art.

The panel 10 may be suitably treated to render the same substantially water-proof. At the outer faces thereof the panel is coated with a layer of thermo-plastic material 13, such as asphalt or the like. At a plurality of spaced areas 14 which are of a size and shape to simulate the face of any selected masonry element, such as a brick face, the asphalt coating 13 is covered with granules 15 of any suitable material. Where a brick face simulation is desired, the granules 15 will preferably comprise small substantially uniform particles of ordinary ornamental or face brick formed by crushing regular face brick and grading the particles for size. Any other desired material such as small stone particles, grit, or the like may also be used.

At the narrow elongated areas 16 between the faces 14, whose size and location correspond to ordinary mortar joints, the coating 13 is covered with granules 17. The granules 17 are preferably of smaller size and of a different color than the granules 15. Also, the areas 16 are preferably depressed so that the granules 17 lie substantially below the plane of the granules 15 and, hence, give a good simulation of a raked mortar joint.

If desired, narrow grooves 18 may be impressed at one or more edges of each of the mortar joint simulating faces 16. As here illustrated, the grooves 18 are formed adjacent the lower edges of all faces 14 except those of the lowermost row or course of said faces on the panel. Also, vertically extending grooves 18 are provided in the vertical mortar joint areas 16 adjacent the left-hand edge of each masonry simulating face 14, except as to those faces 14 which extend to the left-hand edge of the panel. These grooves 18 are preferably so formed as to create an enhanced shadow-line effect, inasmuch as the depth of depression of the areas 17 is obviously limited and may not be sufficient to create a satisfactory actual shadow. The grooves 18 are so formed that the granules 17 line the same and do not expose the color of the thermo-plastic coating 13.

As best illustrated in Figs. 2 and 3, I propose to apply at the edges of the panel, such as the lower and left-hand edges as illustrated in the drawing, a narrow band 19 of granules of a size and color complementary to the granules 17. The granules 19 preferably lie in a plane substantially coincident with the plane of the adjacent edge of the panel 10 and also preferably project slightly outwardly and beyond said panel edge, at least as to some of said granules 19.

When material of the character above described is applied to a wall or other building face with the ship-lap flanges 11 and 12 interfitting as tightly as possible, the granular material 19 on one panel abuts positively against the edge of the adjacent panel. In the event the panels are out of true and any cavity exists therebetween, in the nature of $\frac{1}{32}$ to $\frac{1}{16}$ of an inch, the granules 19 serve to span said cavity and thereby to conceal the existence thereof and also to conceal the color of the thermo-plastic material which would otherwise be exposed at said cavity. In this connection, it would be observed that the 70

thermo-plastic material 13 is sufficiently yielding that the granules 19 may be pressed therein at such points of the panel where full contact between the panels is possible. Hence, the construction involved is one wherein the projection of the granules 19 at the edges is never a disadvantage and will always accommodate itself to small irregularities of the panels 10 occasioned by lack of uniformity in panel manufacture.

When panels of the character illustrated in Fig. 2 are employed, the grooves 18 clearly simulate the joints between the panels and it is practically impossible, without very close and critical inspection, to observe the location of joints between the constituent panels, thus clearly serving the intended purpose and accomplishing the result of obtaining an accurate uninterrupted simulation of the face of a brick wall. While I have found that the existence of the grooves 18 provides the best appearance of simulated masonry, such grooves 18 are not essential. Thus, I have illustrated in Fig. 3 an embodiment of the invention wherein the grooves 18 have been eliminated, and I have found that material so constructed gives satisfactory results and accomplishes the purpose of successfully simulating the face of a brick wall. It appears, however, that material provided with grooves 18 is to be preferred for two reasons. The first of these reasons is that the grooves enhance the simulation of a shadow at a mortar joint. The second reason is the fact that where a cavity exists between abutting panels as above described, there is some slight tendency to give a darkened effect by reason of the fact that the granules 19 are of such shape that they do not accurately interfit, and therefore small interstices exist between them through which a small measure of darkened appearance of the thermo-plastic material within the cavity may be exposed. This latter effect is very small, however, and is fully balanced and complemented by the shadow occurring within the narrow grooves 18 which have the granular material 17 exposed therein.

I claim:

1. Masonry simulating material comprising a plurality of rigid co-planar panels each coated with waterproofing material at one face, granular material of one color covering selected spaced masonry-simulating areas of said waterproof coating, granular material of a second color covering the mortar-joint simulating areas of said waterproof coating between said first named areas, the outermost masonry-simulating areas extending substantially to the edge of said panels at two adjacent panel edges with those in the vertical edge including both full and part size areas, and a narrow band of granular material of said second color at the last named panel edges extending in a plane at an angle to said masonry-simulating areas and interrupted only at the part size areas of the vertical edge, said last named granules projecting outwardly beyond the edges of said panel to span and conceal cavities between adjacent panels.

2. A building covering comprising a plurality of abutting co-planar rigid panels, a layer of waterproofing material coating one face of each panel, granular material partially imbedded in said waterproof layer to conceal said layer, the granular material at spaced selected masonry-face simulating areas of each panel being of one color and that at the mortar joint simulating areas being of a second color and including areas

extending along two adjacent margins of each panel, and granular material of said second color adhered to those portions of the edges of each layer at the two sides of said panel opposite said marginal mortar joint simulations which abut marginal mortar joint simulations of adjacent panels, said last named granular material projecting beyond the plane of the adjacent edge of the panel to span cavities occurring between adjacent panels and cooperating with margin mortar joint simulations of adjacent panels to conceal said cavities.

3. A building covering comprising a plurality of rigid panels of building covering material adapted to be laid in abutting co-planar relation and surfaced with granules of one color at a plurality of spaced masonry simulating areas thereof and with granules of another color at mortar-joint-simulating areas between said first areas and at two adjacent sides of said panels, and a narrow band of granules of said second color extending rearwardly from the granules of said first color on those portions of the side edges of each panel opposite said last named panel sides which abut marginal mortar-joint-simulating areas of adjacent panels, at least some of said last named granules projecting beyond the plane of the panel edges.

4. A building covering as defined in claim 3, wherein at least some of said mortar-joint-simulating areas have narrow grooves formed therein at the edges thereof adjacent at least one margin of the masonry simulating faces with said granules exposed within said grooves to complement the appearance of joints between adjacent panels.

5. A building covering comprising a plurality of rigid panels of building covering material adapted

- to be laid in abutting co-planar relation, said panels being coated at one face with a layer of thermo-plastic material, granules of one color surfacing said coating at a plurality of spaced masonry simulating areas thereof, granules of a second color surfacing said coating at mortar-joint-simulating areas between said first areas and extending at one vertical and one horizontal margin of said panel, said mortar-joint-simulating areas having narrow shadow grooves formed therein, said granules being exposed in said grooves, and a narrow band of granules of said second color adhering to all portions of the edges of said coating at the sides of each panel opposite said marginal mortar-joint simulations which abut marginal mortar joint simulations of adjacent panels, said grooves bearing the same relation to said masonry simulating areas that said granule bands bear to said panels.
6. A building covering comprising a plurality of rigid panels of building covering material adapted to be arranged in abutting co-planar relation, said panels being surfaced with granules of one color at a plurality of spaced masonry simulating areas thereof and with granules of a second color at depressed mortar-joint simulating areas thereof including marginal areas at two adjacent sides of said panels, and a narrow band of granules of said second color surfacing the portions of the edges of said panels opposite said depressed marginal areas which abut marginal depressed areas of adjacent panels, whereby said bands cooperate with said marginal areas of adjacent panels to define a complete mortar joint and to conceal the joint between said panels.
